LUDGER A. O. NICOL AND EUGENE AYOTTE, OF LOWELL, MASSACHUSETTS,
ASSIGNORS TO THE DRAPER COMPANY, OF PORTLAND, MAINE, AND
HOPEDALE, MASSACHUSETTS.

SPINDLE AND BEARING.

SPECIFICATION forming part of Letters Patent No. 608,992, dated August 9, 1898.

Application filed December 28, 1897. Serial No. 663,890. (No model.)

To all whom it may concern:

Be it known that we, LUDGER A. O. NICOL and EUGENE AYOTTE, subjects of the Queen of Great Britain, but residing at Lowell, county 5 of Middlesex, and State of Massachusetts, have invented an Improvement in Spindles and Bearings, of which the following description, in connection with the accompanying drawings, is a specification, like letters on the drawings representing like parts.

This invention relates to spinning-spindles, and has for its object the production of novel means for supporting the bolster within its case and controlling the vertical adjustment 15 of the bolster in a simple and effective manner, the change in the vertical position of the bolster to secure the proper fit of the pintle of the spindle therein being readily accomplished.

20 In accordance with our invention the bolster is supported by a cam-surface located at the upper end of the bolster-case and inclined relatively to the vertical axis of the latter, so that by altering the point of engagement of the bolster and cam-surface the position of the latter is changed vertically.

Figure 1, in vertical section, represents a spindle and bearing with one embodiment of our invention applied thereto. Fig. 2 is a detail in elevation of the upper end of the bolster-case. Fig. 3 is an elevation of the bolster-support shown in Fig. 1, and Fig. 4 is a sectional detail of a modification to be described.

35 Referring to Fig. 1, the spindle S, having a tapering pintle and a whirl W, the bolster-case A, having a threaded shank A' to extend through the rail C, the retaining-nut A², and the bolster B, having within the case a tapering bore to fit the tapering pintle of the spindle, may be and are of well-known or usual construction.

The base of the bolster-case is shown in Fig. 1 as provided with an upturned annular flange a, embraced by the extended base d of a tube D, surrounding and snugly fitting the exterior of the case, the upper end of the support being inclined or slanted, as at d', and preferably serrated or roughened, as best 50 shown in Fig. 3. At its upper end the bol-

ster-case has a longitudinal slot a' therein to receive a pin or projection b on and projecting laterally from the upper end of the bolster B and adapted to rest on the cam-surface formed by the inclined top of the bolster-support D. 55

The lowest part of the cam-surface is shown in Fig. 1 as in engagement with the projection b, and it will be obvious that by turning the support more or less the projection will engage a higher part of the cam-surface, so that the bolster will be elevated and supported in a higher position, to thus adjust the bolster to the pintle of the spindle. 60

The slot in the bolster-case through which the projection b extends prevents rotation of the bolster with the spindle, while the serrated or roughened character of the cam-surface prevents accidental rotative movement of the bolster-support. A step or end bearing 70 F for the spindle is located in the bolster-case independent of the bolster and bolster-support.

Instead of making the controlling-cam as part of a different member, as in Fig. 1, the top of the bolster-case itself may be inclined, as at a⁵, Fig. 4, and more deeply notched, as at a⁶, to receive the projection on the bolster, to thus not only control the vertical adjustment of the bolster, but also to prevent its 80 rotation. In this construction the bolster is turned relatively to the cam-surface to effect vertical adjustment of the bolster. 75

Having described our invention, what we claim, and desire to secure by Letters Patent, 85 is—

1. A bolster-case, a cam located at the upper end thereof, a bolster freely suspended from and supported by the cam, relative partial rotation of the cam and bolster effecting vertical adjustment of the bolster, and means to normally prevent such relative rotation. 90

2. A bolster-case provided at its upper end with an inclined, serrated bolster-support, and a bolster having a lateral projection to engage the bolster-support and be sustained thereby in vertically-adjusted position. 95

3. A bolster-case and a vertically-movable bolster therein, and a concentric bolster-support having a cam to control the vertical ad- 100

justment of and from which the bolster is suspended.

4. A bolster-case longitudinally slotted at its upper end, a surrounding bolster-support having an inclined upper end to control the vertical adjustment of the bolster, and a bolster provided with a lateral projection to extend through the slot in the case and rest upon the upper end of the bolster-support.

5. A bolster-case and a vertically-adjustable bolster therein, and a rotatably-movable tubular bolster-support surrounding the bol-

ster-case and having a cam-surface adapted to engage a projecting portion of and sustain the bolster at its upper end, to control the vertical adjustment thereof. 15

In testimony whereof we have signed our names to this specification in the presence of two subscribing witnesses.
